WEB PERFECTING ROTARY PRESS

Howard M. Barber, Pawcatuck, Conn., assignor
to C. B. Cottrell & Sons Company, Westerly,
R. I., a corporation of Delaware

Application August 10, 1935, Serial No. 35,585

2 Claims. (Cl. 101—179)

In high speed web perfecting rotary presses where quick drying inks and web heating and cooling units are employed, it is very desirable that the several units be so located with respect to each other as to produce the best results while occupying a minimum amount of space.

The object of my invention is to so locate the printing and combined heating and cooling units, the web supply roll and the delivery, that the web can be fed and printed and the inks dried with a minimum travel of the web.

My invention comprises, generally, first and second multicolor printing units, located in line with each other at the opposite ends of the press, each printing unit consisting of an impression cylinder and form cylinders (in the present instance four form cylinders) arranged around its upperside, inking mechanisms for the form cylinders, first and second combined heating and cooling units located in substantially the same horizontal plane, between and below the printing units, each combined heating and cooling unit comprising a heating cylinder and one or more (in the present instance two) cooling cylinders, and a web supply roll located between and in line with the combined heating and cooling units; means being provided for passing the web from the supply roll to and through the first printing unit, then to and through the first combined heating and cooling unit, then to and through the second printing unit, then to and through the second combined heating and cooling unit, and finally directed in the desired direction as, for instance, to a point offset from and at right angles to said units.

A practical embodiment of my invention is represented in the accompanying drawing, in which the figure represents a diagrammatic side elevation of my invention. The first printing unit is herein represented as a four color unit, the impression cylinder being denoted by 1 and its four form cylinders by 2, 3, 4, 5, which form cylinders are arranged around the upper side of the impression cylinder. The inking mechanisms for the four form cylinders are denoted by 2a, 3a, 4a, 5a, which inking mechanisms apply the inks to their respective form cylinders in the usual manner. This first printing unit is located at one end of the press.

The second printing unit for perfecting the web is herein represented as a four color unit, the impression cylinder being denoted by 6 and its form cylinders by 7, 8, 9, 10, which form cylinders are arranged around the upper side of the impression cylinder. The inking mechanisms

for the form cylinders are denoted by 7a, 8a, 9a, 10a, which inking mechanisms apply the inks to their respective form cylinders in the usual manner. This second unit is located at the opposite end of the press.

These two printing units are located in line with each other at the opposite ends of the press at the required distance apart and they are also preferably located in substantially the same horizontal plane.

The first combined heating and cooling unit is herein represented as comprising a large heating cylinder 11 and two small cooling cylinders 12, 13, arranged between the heating cylinder 11 and the impression cylinder 1 of the first printing unit.

The second combined heating and cooling unit is herein represented as comprising a large heating cylinder 14 and two small cooling cylinders 15, 16, arranged between the heating cylinder 14 and the impression cylinder 6 of the second printing unit.

These two combined heating and cooling units are located in substantially the same horizontal plane between and below the printing units.

The web supply roll is denoted by 17 and it is located between the first and second heating and cooling units in line therewith.

The web is led through the press as follows: The unprinted web passes from the supply roll 17 to and through the first printing unit where the web is printed in multicolor upon one side thereof. The web is then led to and around the heating cylinder 11 and cooling cylinders 12, 13 of the first combined heating and cooling unit. From thence the web is led to and through the second printing unit where the web is printed on its other side. The perfected web is then led to and around the heating cylinder 14 and cooling cylinders 15, 16 of the second combined heating and cooling unit.

The perfected web may then be directed from the second combined heating and cooling unit in any desired direction. In the present instance the web is passed around a turning bar 18 and directed at right angles to the press, adjacent the second printing unit.

The means for driving the several units is not shown or described herein. It is understood that the first and second units may be driven separately either for the purpose of "making ready" or for permitting a single or two separate non-perfected multicolor products to be produced.

It is to be understood that guide rolls are

provided for passing the web in prescribed paths from the web supply roll 17 to the delivery.

It will also be understood that any suitable heating medium, such as steam, may be supplied 5 to the heating cylinders 11 and 14 and that any suitable cooling medium, such as water, may be supplied to the cooling cylinders 12, 13 and 15, 16.

It will also be understood that any well known 10 or approved quick drying inks may be used in 15 the printing units.

From the above description it will be seen that I have provided an arrangement of the several units of the press whereby the inks on the freshly 15 printed sides of the web may be thoroughly dried with a minimum travel of the web, the form cylinders of the two printing units at the same time being so positioned that ready access thereto may be obtained.

What I claim is:

- 20 1. In a web perfecting rotary press, first and second multicolor printing units located in substantially the same horizontal plane in line with each other at opposite ends of the press, each printing unit comprising an impression cylinder 25 and form cylinders arranged around the upper side thereof, first and second combined heating

and cooling units located in substantially the same horizontal plane between and below the printing units, said heating and cooling units comprising a heating cylinder and one or more cooling cylinders interposed between the impression and heating cylinders, a web supply roll, and means for leading the web through said units and directing the web therefrom.

5 2. In a web perfecting rotary press, first and second multicolor printing units located in substantially the same horizontal plane in line with each other at opposite ends of the press, each printing unit comprising an impression cylinder and form cylinders arranged around the upper side thereof, first and second combined heating 10 and cooling units located in substantially the same horizontal plane between and below the printing units, said heating and cooling units comprising a heating cylinder and one or more cooling cylinders interposed between the impression and heating cylinders, a web supply roll, and means for leading the web through said 15 units and directing the web therefrom at right angles thereto.

HOWARD M. BARBER.
